UNITED STATES PATENT OFFICE.

JOHN ALEX. PRINCE, OF NEW YORK, N. Y.

AUTOMATIC STOP ATTACHMENT FOR PAPER-EMBOSSING MACHINES.

SPECIFICATION forming part of Letters Patent No. 633,701, dated September 26, 1899.

Application filed November 25, 1898. Serial No. 697,330. (No model.)

To all whom it may concern:

Be it known that I, JOHN ALEX. PRINCE, a citizen of the United States, and a resident of New York, in the county and State of New York, have invented a new and useful Improvement in Automatic Stop Attachments for Paper-Embossing Machines, of which the following is a specification.

My invention relates to an improvement in automatic stop attachments for paper-embossing machines in which the machine is automatically stopped should the paper cling too long to the impression-roller.

My improved stop attachment is operated by means of a normally stationary roller mounted in proximity to the face of the impression-roller, the distance between the roller and impression-roller being such that if the embossed paper should pass around the impression-roller far enough to pass between the two rollers the stop-attachment roller would be operated to stop the machine by the folding of the paper between the impression-roller and stop-attachment roller.

A practical embodiment of my invention is represented in the accompanying drawings, in which—

Figure 1 represents an end view of an embossing-machine with my improved stop attachment applied thereto. Fig. 2 is a partial front view of the same. Fig. 3 is a vertical section through the machine from front to rear in the plane of the line 3 3 of Fig. 2. Fig. 4 is a view of the latch-bar and its adjacent parts, the latch-bar being shown in full lines engaged with its catch and in dotted lines in the position which it assumes when raised by the tripping-arm. Fig. 5 is a view of the same parts, showing the position which they assume after the latch-bar has been released. Fig. 6 is a vertical cross-section in the plane of the line 6 6 of Fig. 5, and Fig. 7 is a detail view of the tripping-arm-operating cam.

My improved stop attachment, which is under the control of the embossed paper as it leaves the impression-roller, is herein shown and described in connection with my stop attachment for use in connection with the paper which is being fed into the machine, which latter stop attachment and mechanism form the subject-matter of Letters Patent No. 615,900, granted to me on December 13, 1898,

for an improvement in automatic stop attachments for paper-embossing machines.

A' designate the side frames of the embossing-machine, between which are mounted an embossing-roll B and an impression-roll C. These rolls are geared together by spur-gears b c exterior to the side frame A. The embossing-roll B is geared to and rotated by a drive-shaft D, suitably mounted in the machine, which drive-shaft is provided with fast and loose pulleys d d'. The drive-shaft D is rotated by a belt E, running to a source of power. (Not shown.)

A belt-shifter F is mounted to reciprocate upon suitable guide-rods f f', extended outwardly from the side frame A, which belt-shifter is provided with a suitable loop f" for engaging the driving-belt E.

A guide-roller G is mounted across the front of the machine in suitable vertically-adjustable bearings g, and a smaller guide-roller H is mounted between the side frames A A' at a point to the rear and slightly below the guide-roller G.

A roll of paper I is wound upon a beam i, which is mounted in supporting-brackets i' on the side frames A A' in front of the guide-roller G. The paper is led over the guide-roller G, under the guide-roller H, and between the embossing and impression rolls B and C, from thence partially around the roll C, and from thence over a roller h, at which point it leaves the machine.

The roller J is mounted in bearings j on the side frames A A', the said roller being located directly above the roller G, the distance between the two rollers being just sufficient to permit paper of the required thickness to pass therethrough without engaging the roller J. A cam K is secured to the end of the shaft of the roller J exterior to the side frame A.

A tripping-arm L is hinged at l to the side frame A, and at its free end the said arm is provided with a roller l', arranged to engage the periphery of the cam K. This cam is provided with a slightly-depressed portion k, within which the roller l' seats, so that the roller J will not be caused to rotate unintentionally—as, for instance, by the jar of the machine.

A rock-shaft M is mounted in bearings m upon the side frame A and is provided with

upwardly-extended arms $m' m^2$, the arm m' having a handle m^3 at its free end. The arm m^2 is connected with the belt-shifter F by a bar m^4 , so that the rocking movement of the 5 shaft M will operate the belt-shifter and cause it to shift the belt from one to the other of the fast and loose pulleys $d d'$ on the drive-shaft. A retracting-spring N extends between the end plate f^3 of the belt-shifter guide 10 and the arm n^2 for shifting the belt from the fast pulley to the loose pulley.

The belt-shifter F is held against the tension of the spring N, with the driving-belt in engagement with the fast pulley d , by means 15 of a latch-bar O, hinged at o to the arm m' of the rock-shaft M, which latch-bar is provided with a suitable notch o' , which is engaged by a catch P, secured to the front of the side frame A. The latch-bar O is provided with 20 a lug o^2 , which rests in close proximity to the tripping-arm L when the latch-bar is held in its locked position.

A roller Q is mounted in adjustable bearings q on the side frames A A'. This roller 25 is located at a point to the front of the impression-roll C and may be adjusted toward and away from the impression-roll until the space between it and the impression-roll is just sufficient to permit the impression-roll 30 C to rotate without rotating the roller Q. The roller Q is connected with the roller J by a belt q' , whereby the rotary movement of the roller Q will be communicated to the roller J.

The operation of my attachment is as follows: If the embossed paper being delivered 35 from the machine from the impression-roll should cling to the said roll until it pass between the impression-roll and the roller Q, as shown in dotted lines on Fig. 3, the roller 40 Q would be rotated, and through the belt q' would rotate the roller J. This rotation of the roller J will cause its cam K to swing its

tripping-arm L upwardly, and which when turned will raise the latch O and release it from its catch P. The retracting-spring N 45 will then rock the shaft M outwardly, thereby causing the belt-shifter to shift the belt from the fast pulley onto the loose pulley, and thus permit the machine to stop.

By the use of this automatic stop attachment 50 the paper which is being delivered from the embossing-machines does not have to be watched by an attendant, for the reason that the machine will stop immediately if the paper should not be delivered properly therefrom.

It is evident that slight changes might be resorted to in the form and arrangement of the several parts without departing from the spirit and scope of my invention. Hence I 60 do not wish to limit myself strictly to the structure herein set forth; but

What I claim is—

In a paper-embossing machine, embossing and impression rolls, means for operating the 65 rolls, an operating-roller mounted in stationary bearings in proximity to the impression-roll at a point beyond where the embossed paper is normally delivered from the impression-roll, the said roller being adapted to be 70 rotated by the passage of the paper between it and the impression-roll, and a stop mechanism under the control of the rotary movement of the said operating-roller, substantially as set forth.

In testimony that I claim the foregoing as my invention I have signed my name, in presence of two witnesses, this 22d day of November, 1898.

JOHN ALEX. PRINCE.
